UNITED STATES PATENT OFFICE

2,679,870

CUTTERHEAD FOR DEBARKING LOGS

William R. Whitlock, Aberdeen, Wash., assignor
of one-third to Clark W. Adams, Aberdeen,
Wash.

Original application August 4, 1948, Serial No.
42,506, now Patent No. 2,591,751, dated April
8, 1952. Divided and this application January
28, 1952, Serial No. 268,536

4 Claims. (Cl. 144—230)

1

My invention relates to improvements in cutter heads for debarking logs, the instant application therefor being a division of my co-pending application, Serial No. 42,506, filed August 4, 1948, now Patent No. 2,591,751, dated April 8, 1952.

The primary object of the instant invention is to provide a toothed cylindrical cutter head for rotation against a log in longitudinally extending position relative thereto and which is mounted for oscillation on a cutter head carrying shaft to compensate for uneven places and bends in the log and equipped with removable and readily replaceable cutting teeth.

Another object is to provide in such a cutter head efficient means for mounting the teeth in longitudinal rows on the cutter head with teeth of the rows easily removed and replaced and interchangeable in the rows.

Other and subordinate objects, within the purview of my invention, together with the precise nature of my improvements will be readily understood when the succeeding description and claims are read with reference to the drawings, accompanying and forming part of this specification.

In said drawings:

Figure 1 is a view in plan, partly broken away and shown in section, illustrating my improved cutter head, the head carrying frame, and the head carrying shaft and parts of a drive for the head carrying shaft and head;

Figure 2 is a view in plan of the cutter head;

Figure 3 is a view in end elevation;

Figure 4 is a view in transverse section taken on the line 4—4 of Figure 2;

Figure 5 is a composite, exploded view in perspective of one of the teeth of the cutter head, the keeper plates and the key associated with said teeth, and

Figure 6 is an end elevation of the same.

Referring to the drawings by numerals, the cutter head of my invention, and designated as a unit by the numeral 53, is mounted, as presently described, in a cutter head carrying frame 51 swingable about a cutter head driving shaft 46 to engage said head 53 with a log, not shown. The frame 51 comprises a pair of side bars 55 connected together by a front tie-rod 56 and a rear tie-rod 59, said bars 55 being swingably mounted adjacent rear ends thereof on anti-friction bearings 57 on the cutter head driving shaft 46. Collars 60 on said shaft 46 prevent lateral play of said bars 55 on said shaft 46.

A cutter head carrying shaft 61 is journaled in antifriction bearings 63 in the front ends of the said bars 55. Belt and pulley drives 64 at oppo-

site sides of said frame 51 extend between the cutter head driving shaft 46 and the opposite ends of the cutter head carrying shaft 61 whereby said shaft 46 drives said shaft 61 to rotate the cutter head 53 by means presently explained. A gear wheel 116 on the cutter head driving shaft 46 provides for operative connection of the same to driving mechanism, not shown, since the same forms, per se, no part of this invention.

10 The cutter head 53 comprises a cylinder 180 with annular heads 181 bolted thereto, as at 182, and provided with annular hubs 183. The cutter head carrying shaft 61 for the cutter head 53 extends through said cylinder 180 and hubs 183. 15 Substantially rectangular teeth 184 with beveled working ends 185 are fixed radially on said cylinder 180 in longitudinally extending rows spaced equidistantly around said cylinder, and by means of segmental keeper plates 186 preferably arranged in series spaced longitudinally of the cylinder 180 and bolted to said cylinder, as at 187. The keeper plates 186 have edge notches, as at 188, straddling the teeth 184 and are also provided with edge keyways 189 for receiving keys 190 also received in keyways 191 in said teeth. After the keeper plates 186 are bolted in place with the notches 188 straddling the teeth 184, the keys 190 may be driven into said keyways 189, 191. The heads 181 may then be bolted in place, and, 20 as best shown in Figure 1, overlap the ends of the keys 190 to hold said keys in place.

The cylinder 180 is mounted on the cutter head carrying shaft 61 by a gimbal 192 having an outer ring 195 retained against an internal shoulder 193 in said cylinder 180 by a bushing 194 held in place in the cylinder 180 by one head 181. The outer ring of the gimbal is thus fixed in the cylinder 180 at the central transverse axis. The gimbal 192 comprises the beforementioned outer ring 195, an inner ring 196, and an intermediate ring 197. The outer ring 195 is pivoted, by a pair of diametrically opposite studs 198, on the intermediate ring 197 which is similarly pivoted by a pair of diametrically opposite studs 199 on the inner ring 196, the studs 199 being co-planar with the studs 198 but in 90 degree angular relation thereto. The outer ring 195 is keyed, as at 200, to the cylinder 180, and the inner ring 196 is keyed, as at 201, on an enlargement 202 on said shaft 61. Bushings 203 on said enlargement 202 and nuts 204 on said enlargement retain the inner ring 196 against slipping sideways. Dust caps 205 are secured to the bushings 203 and to the outer ring 195.

55 The ball bearing assemblies 206 on hubs 183,

the rods 210 and elements 213 are equalizing devices for yieldingly maintaining the cutter head 53 parallel with the cutter head carrying shaft 61, and need merely be identified in passing since the same form, per se, no part of this invention.

As will be seen, the described gimbal 192 provides for universal rocking, or oscillation, of the cutter head 53 laterally on the cutter head carrying shaft 61 to compensate for uneven places and sweeps, or bends, in the log being debarked. The teeth 184 are especially designed to break up bark and knots on a log and brush the same off a log and the described construction of the cutter head 53 provides for easy and quick removal and replacement of teeth 184 in any row.

The foregoing will, it is believed, suffice to impart a clear understanding of my invention, without further explanation.

Manifestly, the invention, as described, is susceptible of modification without departing from the inventive concept, and right is herein reserved to such modifications, as fall within the scope of the appended claims.

Having described the invention, what is claimed as new is:

1. A cutter head for rotation against a log to debark the same comprising a cylinder adapted to be rotated, longitudinal rows of teeth on said cylinder, arcuate keeper plates secured to and fitting flush against said cylinder with edge notches straddling the teeth of the rows, and edge keyways therein, said teeth having keyways therein opposed to the keyways in the keeper plates, and keys slidable in opposed keyways and acting in conjunction with said notches to hold the teeth in place.

2. A cutter head for rotation against a log to debark the same comprising a cylinder adapted to be rotated, longitudinal rows of teeth on said cylinder, arcuate keeper plates secured to and fitting flush against said cylinder with edge notches straddling the rows of teeth, and edge keyways therein, said teeth having edge keyways therein opposed to the keyways in the keeper plates, keys slidable in opposed keyways and acting in conjunction with said notches to hold the teeth in place, and heads on said cylinder fitting

against the ends of said keys and confining the keys therebetween.

3. A cutter head for rotation against a log to debark the same comprising a head carrying shaft adapted to be rotatably mounted, a cylinder surrounding said shaft with the shaft extending therethrough, a gimbal supporting said cylinder in the transverse center thereof on said shaft for rotation thereby and pivotal oscillation laterally about right angularly related axes relative to the shaft, cutter teeth on said cylinder, and means to removably hold the teeth on the cylinder comprising keys extending longitudinally of the cylinder, said teeth having transverse keyways therein engaged by said keys, and heads on said cylinder fitting against the ends of said keys and confining said keys therebetween and being annular and loosely surrounding said head carrying shaft to provide for oscillation of said heads with said cylinder.

4. A cutter head for rotation against a log to debark the same comprising a cylinder adapted to be rotated, longitudinal rows of teeth on said cylinder, arcuate keeper plates secured to and fitting flush against said cylinder with edge notches straddling the teeth of the rows, and edge keyways therein, said teeth having keyways therein opposed to the keyways in the keeper plates, and keys slidable in opposed keyways and acting in conjunction with said notches to hold the teeth in place, a shaft for rotating said cylinder, and a gimbal supporting said cylinder in the transverse center thereof on said shaft for rotation by said shaft and oscillation laterally relative to the shaft about right angularly related axes.
